UNITED STATES PATENT OFFICE.

FRED ARTHUR GREER, OF RUSHVILLE, ILLINOIS.

DRAFT-EQUALIZER.

SPECIFICATION forming part of Letters Patent No. 367,099, dated July 26, 1887.

Application filed May 17, 1887. Serial No. 238,531. (No model.)

To all whom it may concern:

Be it known that I, FRED ARTHUR GREER, a citizen of the United States, residing at Rushville, in the county of Schuyler and State 5 of Illinois, have invented new and useful Improvements in Draft-Equalizers, of which the following is a specification.

My invention relates to improvements in draft-equalizers adapted for three horses; and 10 it consists in a certain novel construction and arrangement of parts for service, fully set forth hereinafter, and specifically pointed out in the appended claims.

In the drawings hereto annexed, Figure 1 is 15 a plan view of my improved equalizer. Fig. 2 is a view in elevation of Fig. 1.

Referring by letter to the drawings, A designates the draft-beam, to which are pivoted two laterally-extending levers, B C, having the 20 singletrees B' C' attached to the extremities thereof.

D designates an equalizing-bar pivoted at an intermediate point of its length to the draft-beam in rear of the levers B C, the said bar 25 having a long arm, d, extending outwardly from the grain and having a singletree, D', attached thereto by a link, D², and a short arm, d', to the extremity of which is attached the pulley E.

G represents a draft-chain, secured at one 30 end to the extremity of the lever B and at the other end to an intermediate point of the lever C, and passing around the pulley E.

The levers B and C being separate, the strain 35 brought upon one of them by the draft-animal will be equalized by the animal attached to the other lever, the draft-chain acting as the medium through which said equalization takes place; and as the levers are of equal 40 lengths and the distance from the end of the lever C to the pulley is much greater than the distance from the extremity of the lever B to the pulley, it is evident that it would require a greater amount of force to be applied to the 45 end of the said lever C than to the end of the lever B to maintain said levers in their proper relative positions. To obviate this, I attach the draft-chain to an intermediate point of the 50 said lever C, thus giving the draft-animal attached thereto greater leverage than the one

attached to the lever B. This enables two animals of about equal strength to exactly balance each other in the draft.

It has been usual heretofore to attach the pulley around which the draft-chain operates 55 either to the draft-beam or to a stationary point—as a yoke or bracket attached to the said beam—and for various reasons it has been objectionable. In my improved equalizer I attach the said pulley to the extremity of an 50 equalizing-bar pivoted to the said draft-beam, and counterbalance the strain brought upon the said extremity by attaching another draft-animal to the extremity of the opposite and longer arm of the same lever or bar, thus 55 accurately balancing the draft and producing a perfect equalizer.

I am aware that it is not new to use laterally-extending levers pivoted to the draft-beam, and also that it is not new to use a draft-chain secured to the said levers and passing around a pulley; but the peculiar arrangement herein described I claim to be new, as herein-after set forth.

Having now described the construction, operation, and advantages of my invention, what I claim, and desire to secure by Letters Patent of the United States, is—

1. In a draft-equalizer, the draft-beam A and levers B C, pivoted thereto, having singletrees B' C', combined with the equalizing-bar D, pivoted at an intermediate point to the beam A, the singletree D', attached to one arm of the bar D, the pulley E, secured to the other arm, and the draft-chain G, passing around 80 the said pulley and attached at the ends to the said levers B C, substantially as and for the purpose set forth.

2. In a draft-equalizer, the combination of the draft-beam A, levers B C, of equal lengths, 85 pivoted thereto, singletrees B' C', secured to the extremities of the levers, equalizing-bar D, pivoted to the draft-beam and having unequal arms d d', to the longer of which is attached the singletree D', and to the shorter of 90 which is attached the pulley E, and the chain G, passing around the said pulley and secured at the ends to the extremity of the lever B and an intermediate point of the lever C, respectively, substantially as described. 95

3. In a draft-equalizer, the combination, with the draft-beam A and levers B C, pivoted thereto, of the pivoted equalizing-bar D, having a pulley thereon, and the draft-chain attached to the said levers and passing around the pulley, substantially as described.

In testimony that I claim the foregoing as

my own I have hereto affixed my signature in presence of two witnesses.

FRED ARTHUR GREER.
